UNITED STATES PATENT OFFICE.

ALFRED RUSSELL HUSSEY, OF HARVARD, MASSACHUSETTS, ASSIGNOR TO AMERICAN WATER SUPPLY COMPANY OF NEW ENGLAND, OF BOSTON, MASSACHUSETTS, A CORPORATION OF MASSACHUSETTS.

CUP-HOLDER.

1,138,758.

Specification of Letters Patent.

Patented May 11, 1915.

Application filed October 3, 1910. Serial No. 584,989.

To all whom it may concern:

Be it known that I, ALFRED R. HUSSEY, residing at Harvard, county of Worcester, and State of Massachusetts, have invented 5 an Improvement in Cup-holders, of which the following is a specification.

This invention relates to cup-holders especially adapted for holding a pile of nested drinking cups which are made of 10 paper and designed to be used once and then thrown away; and is a continuation of my application for Letters Patent, Serial 15 #547,396, yet comprehends an improvement of the cup-holder therein shown.

15 The cup-holder has a circular delivery member provided with means for securing it in upright position, and a circular delivery opening of lesser diameter than the maximum diameter of the cups through 20 which the bottom of a pile of nested cups may normally project, and a vertically disposed cup reservoir of larger diameter than the maximum diameter of the cups, normally closed at the top, which is removably 25 supported on said delivery member, and internally projecting means adapted to engage the pile of cups and to normally retain them with the bottom of the pile projecting downward through the delivery 30 opening and permit withdrawal of the cups from the pile one by one by grasping the exposed portion of the bottom cup.

As the opening is of lesser diameter than the maximum diameter of the cups, the rims 35 of the cups are distorted, being bent inwardly, a crimp being formed in them at the top, which is objectionable, and herein the cup-holder adapted to contain a pile of nested cups has a delivery opening made 40 large enough to permit the removal of the cups without distortion, yet provided with means adapted to be engaged by the bottom cup of the pile whereby said bottom cup closes the opening and supports the cups 45 above it.

To this end the invention consists in providing the cup-holder with a delivery opening of a diameter as large as the maximum diameter of the cups, and providing an elastic ring around said delivery opening which extends inward beyond the wall thereof, having an internal diameter less than the maximum diameter of the cups, which is engaged by the bottom cup of the pile, where-

by said bottom cup closes the delivery opening and supports the cups above it, said ring yielding to permit the removal of the bottom cup of the pile, without distortion, and resuming its normal position immediately to engage the next succeeding cup. 55

Figure 1 is a side elevation of a cup-holder embodying this invention. Fig. 2 is a vertical section of the same. Fig. 3 is a detail of the base plate having the delivery opening. Fig. 4 is a sectional detail, illustrating the removal of a cup. Fig. 5 is a sectional detail illustrating the use of cups 60 without flanges. Fig. 6 is a plan view of a modified form of cup-supporting ring. 65

a represents the base of the cup-holder, 70 which is here shown as the base of a bracket, *a'* being the upright portion thereof which is provided with holes for attaching screws, although other means may be employed for securing it to a wall or other support. 75

The base *a* has a circular aperture *a*² of a diameter at least as large, or larger, than the maximum diameter of the cups *d*, so that the cups will freely pass through said aperture without distortion. On said apertured base *a* a collar *b* is arranged, which surrounds the aperture and has an inwardly extended flange at the bottom, adapting it to be secured to the base. Said collar is designed to receive snugly within it the 80 lower end of a dome *c*, of glass or other material, which is made of suitable length to form an elongated chamber. 85

A circular rubber ring or gasket *g* is placed inside the collar, at the bottom thereof, upon which the lower end of the dome rests, to thereby produce a dust tight receptacle for the pile of nested cups. Said ring is made of rubber essentially for elasticity, yet any other form of elastic ring may be 90 employed which surrounds the aperture. 95

The internal diameter of said ring is less than the diameter of the delivery opening, so that it extends inward beyond the wall of said opening for a short distance, in the 100 form of a lip.

The lip is designed to engage the bottom cup of the pile and to hold said cup with the pile of cups above it, yet to permit of the withdrawal of said bottom cup without distortion, for it will be observed that said lip yields to permit of the withdrawal of the bottom cup of the pile and then immediately 105

resumes its normal position so as to engage the next succeeding cup of the pile. Therefore it is essential that said lip shall be elastic, although, in so far as the ring serves as a packing for the bottom of the dome *c* it need only be yielding. Said lip therefore serves as the internally projecting means to engage the cup or serves as the cup-engaging portion.

10 When the bottom cup of the pile is in engagement with the elastic lip the delivery opening of the cup-holder is closed so that the receptacle, as an entirety, is dust tight; nor is the receptacle opened while the bottom cup is being removed for the lip merely yields to permit of the passage of the bottom cup, and immediately engages the next succeeding cup above it.

15 The ring *g* may have its inner edge notched as shown in Fig. 3, to reduce the stiffness at such part; or it may be devoid of notches as shown in Fig. 6. The cups may have flanges at the top, as shown in Fig. 2, or they may be devoid of flanges, as 20 shown in Fig. 5.

I claim:—

1. A cup-holder consisting of a receptacle adapted to contain a pile of nested cups having a delivery opening of a diameter as 25 large as the maximum diameter of the cups to permit the passage of the cups through it without distortion, said chamber being normally closed except at said opening, and an elastic ring entirely surrounding said 30 opening having its internal diameter less than the maximum diameter of the cups, the bottom cup of the pile engaging said ring to close the opening and said ring yielding to permit said bottom cup to be removed 35 without distortion and returning to normal to engage the next succeeding cup of the 40 pile, substantially as described.

2. A cup-holder consisting of a supporting bracket having an aperture through its 45 base of a diameter as large as the maximum diameter of the cup, and an elastic ring entirely surrounding said aperture and ex-

tended inward beyond the edge thereof, a removable dome arranged on said base above said aperture adapted to contain a pile of 50 nested cups, the lower end of the pile of cups projecting downward through said aperture so that the bottom cup of the pile is accessible beneath the bracket, said bottom cup of the pile engaging the elastic ring to close the 55 aperture, and said ring yielding to permit said cup to be removed without distortion and returning to normal to engage the next succeeding cup, substantially as described.

3. A cup-holder consisting of an apertured bottom plate, a collar arranged on said plate, a rubber gasket arranged within the collar around the aperture and extended inward beyond the edge of the aperture to form an elastic lip, a dome fitted into the 65 collar and resting on said gasket, thereby forming a dust tight receptacle for a pile of nested cups, the lower end of which projects through the aperture and the bottom cup of the pile engages the elastic lip to close the 70 aperture and to support the pile of cups, said lip yielding to permit removal of the bottom cup of the pile without distortion and returning to normal to engage the next 75 succeeding cup, substantially as described.

4. A cup-holder consisting of a supporting bracket having an opening through its base, and an elastic ring entirely surrounding said opening, a dome arranged on said base above said opening adapted to form a 80 chamber to contain a pile of nested cups, the lowermost cup of the pile projecting downward through said opening, so as to be accessible beneath the bracket and engaging the elastic ring to close the opening and to 85 support the pile of cups above it, substantially as described.

In testimony whereof, I have signed my name to this specification, in the presence of two subscribing witnesses.

ALFRED RUSSELL HUSSEY.
